UNITED STATES PATENT OFFICE.

JAMES A. HUDSON, OF NEW YORK, N. Y., ASSIGNOR TO THE I. B. KLEINERT RUBBER COMPANY, OF SAME PLACE.

DUPLEX STOCKING-SUPPORTER.

SPECIFICATION forming part of Letters Patent No. 674,559, dated May 21, 1901.

Application filed November 24, 1899. Serial No. 738,179. (No model.)

To all whom it may concern:

Be it known that I, JAMES A. HUDSON, a citizen of the United States, and a resident of New York, in the county of New York and State of New York, have invented certain new and useful Improvements in Duplex Stocking-Supporters, of which the following is a specification.

This invention relates to garment-supporters; and it consists of a supporting connection device adapted for use in a duplex stocking-supporter and constructed for attachment to the clasp of a corset.

The garment-supporting connection device shown in this application is provided at its upper part with a hook so formed as to be applied to, by hooking into, the loop or eye of a corset-clasp either before said loop or eye is placed over its coöperating stud or after the corset has been applied to the person. The hook of the device is provided with an upwardly-extending tongue or limb arranged to lie behind the loop or eye in such manner as to prevent the hook becoming disengaged from the loop or eye when the garment-supporter is in normal operative position, the whole being so formed as to provide for its ready application to and detachment from the corset.

The supporting connection device or suspension-piece, including the hook at its upper end, is made of a single piece of material, with its lower part of sufficient width to overlap the lower ends of the two sides of the corset-fastener, thus acting thereon to hold this part of the corset down and against the body of the wearer when the device is in operative position, and so also acts as a lock to prevent the accidental unclasping of the corset-clasp.

This suspension-piece thus formed, while it may be made light and strong, is a rigid non-yielding frame that will maintain its shape and always lie snugly against the corset. Its lower part is formed to receive the upper ends of the elastics or tapes of a pair of stocking-supporters which are permanently secured thereto.

This garment-supporting connection device may be made of wire or sheet metal suitably formed into shape and may after the attend-

ing parts or devices are connected to it, if desired, be covered with any suitable fabric.

An examination of the accompanying drawings and following description of the same will fully reveal the nature and construction of this invention.

Figure 1 shows my improved connection device for duplex stocking-supporters applied to a corset. Fig. 2 is a detached perspective view of the metal garment-supporting connection device. Fig. 3 illustrates the manner in which the device may be attached to the loop or eye of a corset-clasp after the parts of the clasp are hooked together. Fig. 4 is a front view of the device, showing a form of the same when made of sheet metal; and Fig. 5 is a side view of Fig. 2, showing also the loop or eye of a corset-clasp in section.

In Figs. 1, 2, 3, and 5 the connection device or suspension-piece *a* is shown formed of wire, its upper part being doubled and bent into hook form *b*, the downwardly-projecting tongue or limb *c* of which performs the holding function of ordinary hooks, and the upwardly-projecting extension or retention tongue or limb *d* is formed in line with the part *c* and so lies back of the loop or eye of the clasp of the corset *h*, when the device is in position thereon, that its upper end bears against the back side of the loop, and so prevents accidental displacement of the hook. The parts are so proportioned that should the device by the rubbing of the clothes thereon or otherwise be raised up the retention-tongue *d* will slide up against the back of the loop *f* to the limit of such movement and the point or end of the limb *c* will still be behind the loop. To remove the hook *b* from the loop *f* with the corset-clasp closed, it is necessary to swing the connecting device *a* into an angular position, as shown at Fig. 3, so that the end of the limb *c* may be moved out of the elongated opening of the loop *f* alongside of the stud *g* of the corset-clasp. This also illustrates how the device may be applied in operative position after the corset is fastened on the person. It will of course be readily understood that this retention-hook device can readily be caught in the loop *f* before the clasp is closed by passing it horizontally through

the loop and that when in the loop it in no wise interferes with the loop being placed over the stud *g*.

The sides of the piece of wire *a* are bent outwardly and downwardly and then inwardly to form the bars *e e* for the attachment thereto of the webbings *j j* of the stocking-supporters, the ends of the wires being then brought together, forming a central brace, and bent or folded around the sides, thus constituting a light, strong, and rigid frame, with the suspension-hook at its upper central part. The suspension-hook by its connection with the loop *f* of the corset-clasp provides one swinging point of suspension for the rigid frame, by which it accommodates itself to all movements of the wearer and equalizes the strains on the two stocking-supporters.

In making the rigid-frame suspension-piece of sheet metal it may partake of the form shown at Fig. 4, having a neck at its upper central part shaped and bent to form the downwardly-projecting part *l* of the hook and the upwardly-projecting extension-limb *m*. Slots *n n* are made in the lower part to form bars, to which the webbings *j j* are attached, and the central portion may be cut away to lighten the device, the lower opening affording means for the connection of other articles to the device, if desired.

The garment-supporting connection device here shown and described may be provided with any other form of hook or catch than that shown at its upper part for attachment to the fastener of a corset, and comprising in one piece of metal such fastening hook or catch; and the bars or loops at its lower edge for the attachment thereto of the webbings or bands of stockings or other garment-supporters result in a rigid frame and produce a strong and unyielding connection between

the webbings of the supporters and the lower part of the corset-fastener, lying, as shown in Fig. 1 of the drawings, over and pressing against the lower parts of the two sides of the 45 corset-fastener.

A covering of fabric or other suitable material, as shown at *i*, may be applied to this supporting connection device in whatever form it may be made. 50

I claim as my invention—

1. In a stocking-supporter, in combination, a rigid frame provided at its upper part with a hook, which comprises a downwardly-projecting limb and an upward extension thereof, said hook being adapted to engage with the loop of a corset-fastener, the upward extension lying behind the loop to prevent the accidental disengagement of the hook therefrom; and a pair of stocking-supporters connected to the rigid frame. 55

2. A stocking-supporter, comprising a front member or part adapted to lie against the lower part of the front of the corset, a pair of stocking-supporters depending by their 65 elastics or tapes from the bottom or lower part of said member, and a hook extending upwardly and rearwardly from the central upper part of the front member or part, consisting of a downwardly-projecting limb and 70 an upward extension, said hook being adapted to engage with the loop of a corset-fastener, the upward extension lying behind the upper part of the loop to prevent the accidental disengagement of the hook from the loop. 75

Signed at New York, in the county of New York and State of New York, this 11th day of November, A. D. 1899.

JAMES A. HUDSON.
